TELEGRAPH SYSTEM AND PRINTING APPARATUS

Louis M. Potts, Evanston, Ill., assignor to Teletype Corporation, Chicago, Ill., a corporation of Delaware

Application November 12, 1942, Serial No. 465,333

19 Claims. (Cl. 178—30)

The present invention relates to printing telegraph apparatus and more particularly to apparatus which utilizes alternating current for operating power for phasing between transmitting and receiving station machines, and also as a fundamental signal carrier.

The principal object of the invention is to provide an alternating current powered and synchronized printing system which is responsive to modulations or modifications of a fundamental alternating current wave for effecting signal transmission.

Another object of the present invention is to produce character printing apparatus which may be operated on a small amount of power such as that transmissible over an ordinary telephone loop circuit and which is controlled by characteristically modifying the power current.

A still further object of the invention is to provide a telegraph system utilizing apparatus which may be manufactured and maintained at low cost and which may be operated at moderate speeds of signal transmission while requiring a minimum of local equipment for maintaining synchronism between transmitting and receiving station apparatuses.

In its basic conception, the system and apparatus of the invention contemplate the use of an alternating current carrier wave preferably having a fundamental frequency of 60 cycles such as is customarily available from commercial sources and having a regulated amplitude sufficient for operating synchronously responsive motors of the rotary or vibrating armature varieties. A certain number of current reversals which are continuously impelling the vibrating motor armature effect the step-by-step operation of a rotary moving element throughout a cycle and this number of undulations accordingly constitutes a signal unit during which a variable number of componental character printing operations may be performed. Upon the fundamental wave there is superimposed at variable positions of a signal span or unit either full or half wave amplitude modifications which effect responses at a receiving station apparatus causing printing character images to be composed by assembling together different combinations of a limited number of character fragments.

In the utilization of this form of signaling, it is proposed that station equipment be provided with apparatus for automatically arresting the printing and transmitting mechanism in a normal or zero position. From this position and with the

5 respective motor elements continuing in vibration or rotation at the regulated frequency, the release or start impulse having the form of a modified full or half wave, as preferred, initiates into rotation a receiving shaft at the printing station which thereupon is adapted to describe a cycle of rotation corresponding to a predetermined number of component alternating current wave impulses. During this cycle of rotation one or 10 more wave modifications or modulations are effected upon the fundamental frequency which cause to be operated at a printer station, a print hammer which is responsive marginally to the superimposed or modified waves. This stronger current at selected periods of the cycle causes character printing to be effected by a composition of printing elements or components.

15 Within the concept of the present invention, each printing cycle consists of a fixed number of alternating current component waves or wave intervals commensurate with the number of character signals which are used in the composition of the alphabet, or if desired, the number of components may be equal to the number of characters in the alphabet in which case each printing symbol may in fact constitute a complete character. Preferably, however, it is proposed here-with to utilize a character printing type wheel 20 that is made up of character fragments. These fragments or component elements may be composed into various combinations so as to form pictorially alphabetical and numerical character representations after the manner of popular convention. It will be understood, of course, that the 25 degree of artistry or perfection of characters will depend upon the number of component elements available within the concept of the system and that for more efficient signal transmission a fewer number of component elements may suffice to obtain comprehensive characterization of the alphabet or numerals.

30 For a more comprehensive understanding of the present invention, reference may be had to the accompanying drawings and to the following detailed specification in which like reference characters designate corresponding parts throughout and in which,

35 Fig. 1 is a perspective view with parts broken 45 away of a vibrating motor telegraph printing apparatus having incorporated therein certain features of the present invention;

40 Fig. 2 is an exploded detail perspective view of 50 a portion of the structural mechanism of the embodiment featured in Fig. 1;

Fig. 14 is a curve chart illustrating several signal examples of prevailing line conditions identified with the systems featured in Figs. 7, 12, and 13.

Referring now particularly to the accompanying drawings there will be described first the structural features and operation of the printing unit illustrated in Figs. 1, 2, 4, and 5. The reference character 42 designates a supporting base which may itself be mounted upon cushioned legs and upon the upper surface of which there is secured a principal supporting wall 43 that extends in a vertical plane transversely of the length of base 42. Wall 43 is profiled so as to afford a clearance at 44, Fig. 1, for the print hammer controlling line magnet generally designated 65, and as at 46, Fig. 5, to permit the extension therethrough of the type wheel carrying shaft 47.

The prime mover which supplies rotary power for the operation of this device consists of a vibrating power shaft 48 journaled within a supporting casting 49, Fig. 4, and carrying at one of its ends in transverse relationship to the shaft 48 the two motor windings 51 and 52, and at its other end a crank pin disc 53 which is mounted concentrically by means of a securing bolt 54 and rigidly held against an anchor plate 55 by means of the securing screw 56 which passes through the arcuate slot 60 of disc 53 and is threaded into the plate 55.

Alternating current from a power source is conducted to the afore-mentioned windings 51 and 52 after a manner already described and disclosed in connection with the apparatus featured in copending application Serial No. 440,653 filed April 27, 1942. As there explained, the windings 51 and 52 are serially connected and wound in a direction so that the opposite pole faces 56 and 57 become alternately and oppositely magnetized

and hence simultaneously attractive to the pole pieces 58 and 59. As the shaft 48 rotates in response to either one of its opposite conditions of magnetization, as, for example, when the pole 56 becomes attracted to the piece 58 and pole 57 to the piece 59, shaft 48 will rotate clockwise as viewed in Fig. 1 and in so doing the end or anchor plate 55 having secured thereto one terminal of a torque spring 61, Fig. 4, causes the latter's convolutions to become distended.

The coil spring 61 thus functions as a tuned reed and the number of its coils which are free, that is, which lie between the point of securement of its first coil in the end or anchor plate 55 and that of an intermediate securement lug 62 may be varied to correspond in natural vibration with the frequency of the current variations and in this way one may regulate the normal periodicity of the spring vibration so that it will accord with the alternating current frequency.

A horseshoe magnet 63 having permanent magnetic characteristics determines the polar magnetic nature of the pole pieces 58 and 59. As a result of the oscillatory movement initiated with the vibrating armature of shaft 48 a corresponding motion is imparted to the crank pin disc 53 in the face of which is secured a crank pin 71 that extends into a slot 72 of a freely mounted pallet arm 73, Fig. 2.

The operation of the vibrating motor is as follows: When starting, alternating current is applied to the device which biases the armature in one direction and places a small torsion on the spring 61. As the current is reversed, this torsion is removed and the force built up in the spring 61 together with the force resulting from the current in the reverse direction cause the armature to be rotated in the opposite direction but to a greater degree since the energy which had been stored in spring 61 now is contributed to the magnetic force of the armature. Because this movement in the opposite direction is somewhat greater than the preceding motion, the energy stored in the spring 61 as a result of this movement is correspondingly greater and contributes to that extent more force when shaft 48, in response to a new reversal of the current, resumes the original direction of movement. The accumulation of energy and, accordingly, the increase in the amplitude of motion continues in this manner until a condition obtains when the energy lost in each swing of the armature and shaft 48 precisely equals the energy added whereupon a constant amplitude obtains.

While a certain amount of current is consumed in attaining or in regaining this maximum amplitude of vibration after a load has been placed and removed, it is notably an energy loss of smaller degree than that amount which would be otherwise required in the performance of the printing operation if no advantage was had of the practice of storing energy from idle oscillation.

While the oscillations imparted to shaft 48 may vary in amount of motion, it is to be noted that the speed of rotation imparted to the type wheel carrying shaft 47 is thereby not affected. This is assured for two reasons, one being that the time of a complete oscillatory cycle does not vary regardless of the amplitude or angle of oscillation, and the other reason being that the crank pin 71 is designed to impart the same degree of movement to arm 73 regardless of its throw 76 or angle of oscillation.

At its extremities of travel, pin 71 leaves the confines of slot 72 and thereafter rides along one or the other of the two arcuate surfaces 74 or 75 depending upon which way it happens to be moving. On its return movement from either direction of travel, pin 71 rides along said surfaces 74 or 75 until it re-enters the slot 72 whereupon it causes arm 73 to reverse its angle of oscillation, repeating the performance in the opposite direction. Accordingly, overtravel on the part of pin 71 beyond a minimum angle of oscillation or amplitude has no effect on the performance of shaft 47 but instead there is assured a constant rotation to shaft 47 by reason of the step-by-step feed mechanism now to be described.

From Figs. 2, 4, and 9 to 11, it will be clear that arm 73 as well as its companion ratchet wheel 77 with which it is integrally associated are together freely rotatable on a bushing or sleeve 78 which is integral with a detent disc 79. The teeth of ratchet wheel 77 are engageable by the spur 81 of a pawl lever 82 pivoted at 83. As best revealed in Figs. 9 to 11, pivot 83 is carried by a trip plate 84 that forms part of a revolute assembly, including the aforementioned detent disc 79.

In this assembly which is carried upon the threaded portion 85 adjacent to the afore-mentioned sleeve 78 is a driving pinion 86, on one side of disc 79. The afore-mentioned plate 84 is held against the shoulder of sleeve 78 by a nut 87 and following it is a type wheel 88 whose periphery comprises a number of flat type carrying faces corresponding to the development indicated in Fig. 3, a lock washer 89 and a retaining nut 91. When the spur 81, which is carried by pawl 82 and which is rotated in a counterclockwise direction above pivot 83 by the influence of a mild tension spring (not shown), engages the teeth of ratchet wheel 77 as the latter member is oscillated to and fro, a step-by-step rotation is imparted to this assembly from the point at which pawl lever 82 is released until the same point at the end of the cycle of rotation when it is again engaged by an arrestment lever. The number of teeth on ratchet wheel 77 is the same as the number of type faces on type wheel 88 and also the same as the number of detent notches in disc 79. Thus, while ratchet wheel 77 remains in the same relative position, as indicated by the surface mark V, Figs. 9 to 11, the type wheel sleeve assembly carrying the pivot 83 of spur lever 82 is advanced in step-by-step manner in a clockwise direction as the spur 81 is pushed from one tooth to another about gear 77.

The rotatable assembly on sleeve 78 comprising the elements afore-recited is supported upon a stud shaft 92 and when pawl lever 82 is held in its clockwise extreme position as designated in Fig. 9 by reason of the engagement of its tail portion 93 by the disc extremity 94 of a pivoted lever arm 95, no rotation of the assembly is obtained. However, as soon as the disc lever 95 is withdrawn (counterclockwise) which operation is effected by a tripping of its associated lever arm 96, as will later be explained, the tail 93 of pawl 82 is permitted under the influence of the latter member's spring 90 to move in a counterclockwise direction about pivot 83 until the spur 81 enters into the field traversed by the oscillating teeth of ratchet wheel 77. Each angle of advancement, that is when one of the teeth of ratchet wheel 77 engages the spur 81 and sends it one tooth distance in a clockwise direction, Figs. 9 to 11, about shaft 92, is retained and the return movement is prevented

by reason of a detent 97, Fig. 5, mounted on the spring 98 which acts against the surface of notched detent wheel 79.

Lever arm 95 which is pivoted on a screw 99 together with its associated lever arm 96 is urged by spring 100 in a clockwise direction about its pivot until its opposite extremity (shown in dotted outline in Fig. 9) engages a sidewardly extending lug 101 integral with lever arm 96. This spring effects the unified action on the part of levers 95 and 96 subject to the yield afforded by said spring 100. Levers 95 and 96 may, therefore, be considered to act as a unit and moreover lever 96 is provided with a sidewardly extending lug 102 which is engaged by a downwardly urging coil spring 103 which imparts to the lever assembly 95-96 a counterclockwise torque about pivot screw 99 as a center.

The extremity of lever 96 is provided with an upwardly jutting lug 104 which is engageable by a downwardly extending projection 105 integral with the rotatable trip plate 84 of the assembly, Fig. 2. Also, the lowermost extremity of lever 96 is shouldered as at 106 and thereat is engaged by a hook 107 that terminates one arm of a trip lever 108 pivoted at 109. Lever 108 is spring urged in a counterclockwise direction and its other arm is provided with a sidewardly extending shelf 111 that is, in turn, engaged by an adjustable trip screw 112 carried in a ledge of the downwardly extending branch 113 of an armature 114.

Armature 114 is supported by an anchor plate 115 through the medium of a flexible tongue 116 connecting the two. This armature which corresponds to the representation designated 64 in Fig. 8 carries at its extremity a print hammer or anvil 117, Fig. 5, which is adapted to strike against the type wheel faces 118 to 133, Fig. 3. Beneath the plate 115 is located a permanent magnet 134 and since this element is mounted between the plate 115 and another plate of electromagnetically permeable material 135 connecting it to the core 136 of an electromagnet 65, a primary magnetic field is thereby set up affecting armature 114 preferably so as to bias it downwardly as viewed in Fig. 1. For a theoretical explanation of the operation of this portion of the apparatus, reference will now be had to Fig. 8 in which symbolic representations of a transmission system are indicated in conjunction with a simplified communication circuit.

The particular system of telegraph transmission now under discussion involves specifically the use of a tuned vibrating-armature type of motor which is adaptable for use with alternating current, though any other class of synchronously driven motor may with but slight changes for adaptation purposes, also be used. One of the special functions of printer control now to be described is that of print hammer operation, a performance which, in the instant system, may occur one or more times during each cycle of rotation of the element which carries the type wheel.

In Fig. 8, the print hammer has been designated 64 and indicated as an integral element of the biased armature of polar magnet 65 situated at a receiving station designated generally 67. At a transmitting station, alternating current is obtained from a frequency regulated source. Also at this source, signaling power is obtained as through the use of a fixed voltage transformer 66 whose secondary winding is grounded at one terminal and connected to line

68 at its other terminal after passing through a resistance 70. The latter element limits the current flow over line 68 to an amount which is marginally insufficient to operate the biased print hammer control magnet 65 because of a bias (described later) influence but is sufficient to actuate the vibrating armature at the receiving station in series with the magnet 65. When the marginal control resistance 70 is shunted out, as by the closure of contact pair 69 of the transmitter keyboard apparatus, then an increased current flow is passed which does overcome the magnetic bias of armature 64, and as a result the latter member will be attracted during strong current pulsations and effect composition printing accordingly.

The print hammer 64 and its integrally associated armature is normally held away from the type wheel and against the influence of a biasing spring and while in this position the normal and relatively weak alternating current pulsations, prevailing when no character printing signals are superimposed upon the primary wave, are insufficient to effect the movement of the armature. However, when an amplified signal impulse is received over the line as upon the closure of the contact pair 69 at the transmitting station, armature 64 is impelled by the increased current which overcomes its bias and causes it to strike the type wheel during either the plus or minus half of a full alternating current wave, according to the manner in which the magnet winding is designed.

For some purposes it may be preferable to design polar magnet 65 so that the first half wave (plus or minus) of a complete alternating current wave will actuate this armature into performance affording the second half wave interval as time in which to restore the armature fully to its unoperated position. In this way, there may be avoided a condition whereby the initial portion of a signal contributes an additional bias force in a direction toward the unoperated position which then must be overcome as an additive force to the normal magnetic bias during the second half wave of a cycle. Tests have proved, that satisfactory supervision of a biased armature print hammer may be had under either conditions of polarity print magnet control.

The present system utilizes a fundamental alternating current frequency wave represented in Fig. 6 by the reference character 16 and designated by the legend Fundamental Wave. This recurring undulation may be transmitted uninterrupted to a receiving printer and its effects upon a synchronous wound motor or upon a vibrating armature type of motor as is specifically illustrated in the accompanying drawings, is to maintain in motion the station's apparatus with the regularity of the current stabilization factor. The manner of signaling in accordance with the herein proposed system consists in a practice of superimposing a wave amplitude modification or modulation as designated for example by the undulations in the curves A, B, and I, whereat a unit cycle of operation is designated by a total of sixteen intervallic divisions. These divisions are comprised of fourteen signaling intervals (each interval of which is made up of a full alternating current wave; that is, two half waves of opposite polar characteristics) and two additional signal intervals designated in Fig. 6 by the legends Stop and Start. While the transmission cycle is made up of sixteen intervals as portrayed by the curves in Fig. 6, the receiver cycle is made

up of but fifteen intervals or components as designated by the faces 118 to 142 of the type wheel development, Fig. 3. Fourteen of these components correspond as do the transmission components, to the fourteen printing fragments 118 to 133, while the fifteenth interval corresponds to the start interval of the transmission cycle. Where the receiver cycle is not provided with a sixteenth interval to correspond with that of the transmission cycle, the receiving printer will rest and thereafter be initiated into a new cycle upon the receipt of the start interval. Thus, during continuous signal transmission the printer shaft will be momentarily brought to rest after each cycle during an intervallic instant which corresponds in duration to one full wave length.

As may be noted, each one of the charted signals consists of a full wave modulation during 20 its "start" interval. Thereafter the occurrence of amplitude modulations varies in accordance with the characteristics of the particular signal code or composition of character fragments. The signal composition of the instant system consists 25 in a number of wave modulations occurring during the respective component interval of which there may be one or more within a band of intervals termed a cycle, which intervals coincide with fragmentary symbols that may be composed 30 to make character designations.

Referring now to the illustration, Fig. 3, there is indicated an exemplary arrangement of character composition fragment or character elements, fourteen in number. The letter A of the alphabet 35 will, in accordance with the illustration of Fig. 1, consist of an amplitude modulation in the first, fourth, sixth, eleventh, and fourteenth intervals which accordingly will be composed of the character fragments illustrated in the developed type 40 wheel, Fig. 3, of the faces designated thereat 118, 122, 124, 129, and 133. A composite alphabetical character made up of these fragments of printing elements in the designated order will produce a character that may be readily identified as the 45 alphabetical representation A and after the same manner alphabetical characters B, C, etc. may be composed as may also the numerical integers 1, 2, 3, etc. from the representative arrangement of fragments as designated in Fig. 3. Where a different style or artistic composition of intelligence 50 characters is desired any other pattern differing from the one shown may be produced with perhaps a different number or a more commodious supply of character elements. For the purpose of 55 obtaining a simplified and yet readily discernible alphabet and Arabic numeral series, fourteen character fragments as shown in Fig. 3 have proved ample for practical comprehensions.

Referring now again to the illustration in Fig. 5, 60 the printing armature 114 vibrates between the poles 137 and 138 of the magnet core 136. Normally, that is, when the operating current wave is received through the winding 65, armature 114 remains dormant preferably resting against the 65 bottom pole 138 and does not then respond by vibrating between its two limit screws 139 and 141. This is the condition which prevails when no signals are induced upon line 68.

In response to the amplified wave impulse, armature 114 moves from its rest position as indicated in Fig. 5 to its opposite position whereat its extremity abuts limit screw 139. This operation of the armature will in all instances but one result in the printing of a mark upon the 75 tape that passes between the type wheel 88 and

anvil 117. The exception prevails at the particular instant that the blank type face 142 is disposed in printing position and this space is called blank because it is provided with no print marking impressions as are the other faces 118 to 133. As a result of the upward movement of portion 113 of armature 114, screw 112 engages the shelf 111 of bell crank lever 108 rocking the latter member clockwise about its pivot 109 and releases its hook 107 from the shoulder 106. This frees lever arm 96 to the influence of its spring 103 and as a result lever 96 as well as its companion lever arm 95 rock in a counterclockwise direction about 99 as a center.

In consequence of the movement of lever arm 95, its disc extremity 94 is withdrawn from engagement with the tail 93 of pallet lever 82, permitting the latter's spur 81 to move into position so as to be engaged by the teeth of ratchet wheel 71. Thereafter the oscillations of shaft 48 will no longer be idle but instead have the effect of imparting motion to the type wheel carrying assembly, Fig. 2, by reason of the reciprocal action of crank arm 73 and the step-by-step movement of ratchet wheel 71.

For the duration of one revolution, each succeeding oscillation of shaft 48 will be translated to crank pin 71, arm 73, and ratchet wheel 71 as a single-step movement in a counterclockwise (Fig. 2) direction of the type wheel carrying assembly. Each such single-step advancement of said assembly is held by the spring-urged detent 97 which engages the notches of detent disc 79. Also, it is to be noted that as the assembly rotates in a counterclockwise direction, plate 84 being a part of the assembly also describes a cycle of revolution carrying with it engagement tooth 105.

During the cycle of rotation of the type wheel assembly, one or more additional amplified waves 40 or strong impulses will be received causing armature 114 to vibrate between its limit screws 139 and 141 but during the other positions of the cycle, anvil 117 will strike against one or more of the faces 118 to 133. Also during the cycle of rotation, spur lever 82 will be carried around together with its pivot 83 of plate 84 describing a revolution as it does so in a counterclockwise direction until a point is reached near the end of its cycle when its tail or rearmost extremity 93 comes into engagement with the disc 94 which will meanwhile have been replaced to its original position as will now be explained.

Near the end of the cycle of revolution, projection 105 of plate 84 encounters the upstanding extremity 104 of lever arm 96 camming the latter member in a clockwise direction about its pivot 99 until hook 107 re-engages the shoulder 106. This point of engagement occurs after the fourteenth cyclic interval since lever 108 must not again be released until after it has reached the stopping point in contemplation of a new signal.

The driving pinion 86 which is integrally formed with a detent disc 79 meshes with a drive wheel 143 of a tape feed shaft 144. While the assembly, Fig. 2, is making one cycle of revolutions in a counterclockwise direction, wheel 143 and its integrally associated shaft 144 will describe a few degrees of rotation in a clockwise direction, as viewed in Fig. 1.

At its foremost extremity, shaft 144 carries a fluted portion 145 for affording a frictional engagement with the undersurface of the tape 146 which is threaded through the guide members 147 and 148. Cooperating with the fluted extremity 75 a

145 is a pressure roller 149 carried upon an arm 151 which is pivoted at 152 and urged in a counterclockwise direction by a pressure spring 153. The tape after being pulled up to the point of contactual engagement between fluted roller 145 and pressure roller 149 is pushed thereafter beneath the type wheel 88 and the printing region just above the anvil 117 exiting through another guide 154.

10 The printing tape is supplied from a roll 155, Fig. 1, carried upon a shaft 156 between the two vertical guide strips 157 and 158 that are suitably supported upon the base 42 of the machines. The tape 146 as it emerges from the periphery of the roll 155 passes through a slotted opening 159 in the supporting wall 43 and thereafter doubles around the edge of the forty-five degree guide plate 161 changing its direction at right angles thereat and entering the first guide member 148.

On the accompanying illustrations no specific ink depositing medium has been shown in order to avoid obscuring the views. Several methods of ink supply might be used in conjunction with printer type wheels of the class employed such as an ink reservoir roller contacting an ink distribution roller which in turn contacts wheel 88, or an ink ribbon may be fed between the anvil 117 and the type wheel 88. Ideal results have been obtained by utilizing a double paper strip, on one web of which there is carried a carbon deposit that is transferred through impact upon the surface of the other strip.

For a general understanding of the practical application of the present invention in a system designed especially for signal transmission of alternating current fundamental wave signals having character selecting modulations or wave modifications, reference will now be had to the specific illustration in Fig. 7 showing a typical circuit arrangement having embodied therein a central office exchange system. In this illustration, reference character 11 denotes in dotted outline a central office exchange system provided with the commercial alternating current supply lines 12 and 13, a power transformer comprised of the windings 14 and 15, and a pair of balanced induction control transformers 16 and 17 forming part of a cord circuit in the manual exchange system or part of a link circuit in an automatic exchange system. Characters 18 and 19 indicate two illustrative outlying or subscribers' stations represented by dotted rectangles of which there may be any number similarly communicating with the central station equipment.

At each outlying station 18 or 19 there may be provided a keyboard transmitter apparatus as well as a receiving printer, the latter for recording both outgoing and incoming communication signals. At said stations 18 or 19, the keyboard transmitting equipment is represented by the motor armatures 23 and 23a which are indicated as being in series circuit connection with a printer motor armature 24 and 24a from a center tap of local primary transformer windings 25 and 25a whose secondary windings 26 and 26a are in circuit with a printer operating magnet 27 and 27a.

The keyboard apparatus at each of said stations is adapted to supervise a pair of transmitting contacts 28 and 28a which lie in one of the lines 29 or 31 which line may form part of a pair of lines connecting each outlying station

with a central office 11, the other lines of said pairs being designated 32 and 33, respectively.

Outlying station 18 is connected over its line 29 to one terminal of a winding 34 of the central station transformer generally designated 17 while its other line 32 is connected with one terminal of the winding 35 of another central station transformer generally designated 16, the adjacent terminals of said windings 34 and 35 being connected together and joined thereat by a line 36 from one of the terminals of the power transformer's windings 15 whose opposite terminal extends through a filter condenser 37 to ground. In correspondence therewith, outlying station 19 is connected over its lines 31 and 33 with the opposite windings 38 and 39 of the transformers 17 and 16, respectively, and these windings are connected together at their opposite terminals and also over line 36 to the winding 15 of the power transformer as afore-described.

In accordance with this arrangement of elements, alternating current supplied from lines 12 and 13 induces a secondary voltage in the winding 15 which is carried over line 36 to the two windings 35 and 39 of transformer 16, whereby each neutralizes the magnetic effect of the other of the two windings resulting in zero impedance. These secondary power current pulsations travel in opposition to each other over windings 34 and 35, but in the same direction over lines 29 and 32 to the mid-point of local transformer primary winding 25, it being noteworthy that because current flows in the same phase over lines 29 and 32 to the halves of winding 25, no current will be induced upon the transformer secondary winding 26, but the secondary pulsations from coil 15 without appreciable impedance loss will traverse in series the windings 24 and 23 of the vibrating printer motor and transmitter element to condenser filtered ground. When the stations 18 and 19 are in communication with each other and while the signaling contacts 28 and 28a remain closed, the current undulations over lines 32, 33, 29 and 31 are continuous sine wave undulations as portrayed by the curve 101, Fig. 14, no distinction being noted in any of its waves at this time whereby the length of a signal interval is set off or defined.

When signaling is initiated as by opening of one of the contact pairs 28 or 28a, depending upon the direction of communication, then corresponding breaks in the line 29 and interruptions in line 31 are effected so that the resulting pattern of the alternating current wave on these lines for the character A is after the manner illustrated in the curve 102, Fig. 14. As a consequence of the intermittent line breaks or interruptions, current surges obtain over the companion conductors 32 and 33 with the result that on these lines the signal pattern is such as is portrayed by the curve 103, increasing the amplitude of both lobes of each full wave during those component intervals of each signal in which no current obtains on the lines 29 and 31. Since the effect of coils 25 and 25a of inducing a secondary voltage on the windings 26 and 26a, obtains only during the signal intervals of interruption, that is, when the contact pairs 28 or 28a are open, then it follows that print magnets 27 and 27a are energized by an alternating current wave induced from the primaries 25 and 25a during the break intervals as best portrayed by the curve 104.

Since the secondary winding 15 of the power

transformer is connected in a similar manner with station 19 through the afore-described circuit connections with coils 38 and 39, no current will be induced upon the secondary winding 26a of that station's printer magnet 27a. As a result of the neutralizing effects of each half of the windings of local transformer coils 25 and 25a upon the other half, no magnetic circuit is established on either side of these transformers; moreover, because winding 35 opposes winding 38 and because winding 34 opposes winding 38 there prevails a minimum of impedance in the respective legs of these circuits so long as the described balance is maintained. The opening of one of the circuit legs by reason of the separation of contact pair 28, for example, will, however, cause current to be induced upon one of the secondary windings, as will now be described.

With the opening of one of the transmitting contact pairs such as contact pair 28, there is not only removed one of the balancing halves of the coil 25, permitting the other half to actuate magnet 27, but, through effectively removing from the circuit its coil 34 of transformer 17, the winding 38 is permitted to act as an impedance and to reduce the current in circuit 31. The major portion of current from supply line 36 is thereby diverted and flows over the other leg 33 of the parallel paths and through the winding 39. In consequence of this effect, and since the impedance of coil 38 reduces the current flow through the leg 31, current is increased through leg 32 causing the upper half of transformer winding 25a to induce a voltage upon the secondary winding 26a at station 19. The secondary windings 26 and 26a are illustrated as being directly connected to the print magnets 27 and 27a importuning thereby that these elements are operated in response to the induced alternating current. It is believed well established that where it is deemed advantageous to operate the print magnets by means of direct current, the appropriate rectification of the induced signal may be had by well-known practices whereby the alternating current signal may be converted into a direct current signal simulating conventional simplex communication practice.

In communication held in the reverse direction the opening of contact pair 28a through the operation of the keyboard at station 19 will have a corresponding effect upon the receiving printer magnet 27 at station 18. Thus, there is described a system of telegraph communication in which a central station supplies the operating and signaling current to a plurality of outlying subscribers' stations.

A further modification in which the present invention finds particular application is featured in Fig. 12 wherein there is illustrated a central station 143 and two respective outlying stations 144 and 145. In this system alternating current originates at a source 146 in the central office and is impressed through the primary winding 147 of a power transformer upon a pair of secondary windings 148 and 149 serving stations 144 and 145, respectively.

Each one of the subscriber or outlying stations 144 or 145 is connected with the central office by means of a pair of conductor lines 151 and 152 or 151a and 152a, as is noted in Fig. 12. Lines 151 and 152 leading to station 144 form part of a loop circuit having the afore-described power transformer secondary winding 148 in series with a pair of additional transformer windings 153 and 154. Each loop circuit also consists of a pri-

mary winding made up of two halves designated 155 and 156 between which a midpoint tap connects over a line to the motor windings 157 and 158 of the printer and transmitter mechanisms respectively. The corresponding several elements at the other outlying station 145 are designated by similar symbols and marked with corresponding reference numerals having the auxiliary reference suffix *a*.

Windings 155 and 156 oppose each other inductively when the loop circuit 151—152 is closed and under such conditions no current may be induced upon the local station transformer secondary winding 159 because the two halves of the parallel circuit neutralize each other up to the midpoint betwixt the windings 155 and 156. However, when this balanced condition is destroyed, due to the opening of one side 151 of the parallel circuit upon operation of the contact pair 161, then the lower circuit 152 remains closed and a condition obtains in which the entire surge of current is directed over wire 152 effectively constituting the half winding 156, a primary of the local station transformer.

Thereupon, an induced voltage is communicated to the print magnet 162. Moreover, as a result of the opening of contact pairs 161, it is to be noted that current ceases to flow in winding 153 and because of this, no current is induced into winding 153a, as is previously had, due to the fact that windings 153 and 153a are balanced inductive windings. Therefore, at station 145 a parallel condition is created destroying the balance between its lines 151a and 152a so that the upper half winding 155a is without current while the lower winding 156a obtains a preponderant surge from the secondary 149. As a consequence, current is increased in the secondary winding 154a by induction from the primary 154 and since the circuit which includes secondary winding 148 is at this time open, the drain in the power transformer is accordingly relieved to this extent and the current flowing through the secondary winding 149 is correspondingly increased. Therefore, the current flowing through half winding 156 which is in series with the secondary winding 154 is increased causing a stronger secondary current to be induced upon the transformer secondary winding 159.

It is to be noted again that because no current is induced upon the secondary winding 153a by the primary winding 153 due to the open condition at contact 161, no current is available in circuit 151a of station 145. This momentarily destroys the balance of the circuits 151a and 152a in the same manner as obtained in connection with circuits 151 and 152 and with the same results upon secondary winding 159a and the related print magnet 162a.

Thus, under normal conditions with stations 144 and 145 connected together for intercommunication through an automatic or manual switchboard arrangement, alternating current from the common source may be obtained parallelly over circuits 151 and 152, windings 157 and 158 causing the latter motor elements to attain a vibration frequency in correspondence with that communicated to any other station in the system. When signal generation is started as by the opening of contact pair 161, then without interrupting the vibration frequency which is thereafter available over but one-half of the windings 155 and 156, there is caused to be induced a further signal line control upon the print magnet 162 so as to pro-

duce a record simultaneously at the two stations 144 and 145.

In this system as with the one described in connection with Fig. 7, a normal signal pattern prevailing over lines 151 and 152 is represented by the curve 101, Fig. 14, and during such intervals when the balance is destroyed, the alternating current wave undulations become characteristically accentuated after the manner of curve 103 on lines 152 and 152a. The alternating current impulses prevailing over the open lines 151 and the reflected condition on its opposite line 152a is such as portrayed on curve 102.

As with the case of the Fig. 7 embodiment, 15 alternating current is induced in the print magnets 162 and 162a in broken wave portions as represented by the curve 104 to produce the character A, it being obvious that where a direct current in the alternate control circuit is preferred, conventional rectification practices may be employed to obtain such results.

In Fig. 13, a print hammer designated 164 is indicated as an integral element of a biased armature under the control of an electromagnet 165 at a receiving station 167. Alternating current is obtained from a common regulated source at both the receiving station 167 and the transmitting station 166. The vibrating frequency of such source should be regulated with exactness, although where such frequency may be obtained from two different sources of supply, satisfactory results of operation can be obtained without identical phase conditions obtaining at all times.

The contact pair 169 which is normally open is periodically closed in accordance with the operation of a keyboard apparatus and its performance may be identical with that of contact pair 161 described above. Upon the closure of such contact pair, a circuit 168 is completed for energizing print magnet 165 which thereupon actuates its armature 164 causing it to strike against the type wheel at precise cyclic instants coinciding with the presentation of character printing fragments on its periphery. The curve representing the signal transmitted over line 168 is designated 105 on the chart, Fig. 14, and it is to be noted that the induced alternating current of magnet 165 resembles that of magnets 162 and 27 discussed above. The instants at which armature 164 is forced against the type wheel may correspond with the first or second half cycles of each double lobed wave. This will depend upon the design characteristics of magnet 165. In other words, for some purposes it may be preferable to arrange polar magnet 165 so that the first half-wave of a complete alternating current cycle will actuate its armature affording the second half-wave as time during which to assist the restoration of the armature to its unoperated position.

While the present invention has been explained and described in contemplation of a specific embodiment, it is to be understood nevertheless that numerous modifications and variations may be incorporated without departing from the essential spirit or scope thereof. Accordingly, it is not intended to be restricted to the particulars of the accompanying drawings nor to the particular details described in the foregoing specification except as indicated in the hereunto appended claims.

The invention claimed is:

1. In a printing telegraph apparatus, a type wheel carrying shaft, a tape advancing shaft, said shafts motor driven by alternating electrical energy received over a line, a type wheel carry-

- ing fractional sign elements to be integrated during signal composition, a print hammer, and means responsive to cyclic amplitude variations in said electrical energy for actuating said print hammer under control of said amplitude variations and at variable cyclic intervals during a single rotation of said type wheel carrying shaft for producing an integrated character.
2. In a printing telegraph system, a type wheel having a plurality of type producing fragments each capable of printing an alphabetical or numerical character portion, means responsive to the undulations of an alternating current wave for advancing the fragments on said type wheel successively before a printing position, and a print hammer responsive to variations in said alternating current wave for effecting printing engagement during corresponding character fragment presentations.
3. In a printing telegraph apparatus, a type carrying member including a plurality of character printing fragments, each shaped to reproduce a part of an alphabetical or numerical character image, means for presenting said character fragments sequentially in printing position, a print hammer, and electromagnetic means responsive to impulse modulations induced upon an operating power line for actuating said print hammer to selectively engage said character fragments.
4. In a system of printing by character fragment composition, the combination including a type wheel having a plurality of printing fragments distributed peripherally thereon at regular angular intervals, a pulsating motor for operating said type wheel to present its printing fragments in sequence, and a print hammer responsive marginally to superimposed current modulations for bringing a strip of material into engagement with corresponding ones only of said character fragments.
5. In a printing telegraph apparatus, a type carrying member having a plurality of fractional printing elements to be integrated during signal composition, motive power means driven by the undulations of an alternating current received over the line for driving said type wheel, a percussion printing member, and means nonresponsive to the regular undulations of said alternating current wave, but responsive to cyclic amplitude variations of said current and effective to engage said type wheel in response to said cyclic amplitude variations for producing an integrated character.
6. A printing telegraph apparatus comprising a rotary type wheel having a plurality of peripherally disposed character printing fragments, means to advance said type wheel in accordance with groups of successive undulations of an operating current so as to cause to be presented said type wheel fragments at a printing zone in cyclic phase relationship with said wave undulation groups, a striker normally nonresponsive to said current undulation, and means responsive to a superimposed undulation of greater amplitude for actuating said striker in accordance with the presentation of corresponding ones only of said printing fragments.
7. In a printing telegraph mechanism, apparatus for advancing a strip of material in step-by-step movements past a printing zone, a type carrying wheel having a plurality of type elements each presentable for printing opposite said material during brief rest intervals and between said successive strip advancing movements, a vi-
- brating motor responsive to alternating current for actuating said type wheel and said tape advancing mechanism at regulated speed, and a print hammer responsive to superimposed current modulations and normally inert to normal alternating current modulations for effecting printing of said type wheel elements accordingly.
8. In a printing telegraph apparatus, a type carrier provided with fractional sign elements to be integrated during signal composition, a print hammer, motor means driven by continuous alternating electrical energy variations received over a line for moving said type carrier in continuous step-by-step movements, and means responsive to predetermined cyclic amplitude variations in said alternating electrical energy for actuating said print hammer at various intervals during each rotary cycle of said type carrier for producing an integrated character.
9. In a printing telegraph system, a type member having a plurality of character image composing fragments for printing alphabetical or numerical characters, means responsive to the undulations of an alternating current wave for advancing the fragments on said type member sequentially through a printing location, and a print hammer responsive to variations in said alternating current wave for effecting printing engagement during corresponding character fragment presentation at said location.
10. In a printing telegraph apparatus, a carrying member including a plurality of character composition fragments, each shaped to reproduce a portion of one or more alphabetical or numerical characters, means for presenting said fragments sequentially in printing position, a print hammer, and electromagnetic means responsive to irregularities induced upon an operating power line for actuating said print hammer to selectively engage against corresponding ones of said carrying member character fragments to effect printed character composition.
11. In a system of printing, the combination including a type wheel having a plurality of fractional character elements distributed peripherally thereon, said elements adapted to be integrated during signal composition, an alternating current motor for operating said type wheel to present its typing elements successively to the printing locus, and a print hammer responsive to the cyclic amplitude modulations superimposed upon the normal cyclic undulations of an alternating current wave for striking against said type wheel correspondingly to produce an integrated character.
12. A printing telegraph apparatus comprising a cyclically rotatable type wheel having a plurality of character printing fragments, means to advance said type wheel in accordance with successive undulations of an alternating current so as to cause to be presented said type wheel fragments sequentially at a printing zone in phase relationship with said wave undulations, a striker, and means responsive to superimposed undulations for actuating said striker in accordance with the presentation of corresponding ones only of said printing fragments.
13. In a printing telegraph mechanism, apparatus for advancing a strip in step-by-step manner, a type carrier having a plurality of type elements, means for printing by striking said strip against said carrier elements during brief rest intervals and between said successive tape advancing movements said means including a print hammer responsive to superimposed current

modifications but normally inert to normal alternating current modulations, and a vibrating motor for actuating said type carrier and said strip advancing mechanism.

14. A telegraph printing mechanism, power driven and selectively controlled by an alternating current sent over a line, comprising a carrier of character printing fragments, a motor responsive to the alternating current for moving said carrier so as to present successively all of its fragments before a printing zone, and a print hammer including means responsive but marginally to electrical variation produced upon the current for striking against said fragments correspondingly.

15. In a system of telegraphic signaling, a telegraph motor element having a period of vibration coinciding with a predetermined alternating current frequency constant, telegraph receiving apparatus actuated by said motor element including means responsive to an initial wave modulation and means responsive to ensuing wave modulations, transmitting control means for superimposing initial wave modulations upon said current, and signal forming means responsive to subsequent supervision for superimposing said ensuing modulations upon said current.

16. In a printing telegraph system, a transmitter station, a receiver station, means for supplying a current of fundamental wave frequency on a transmission circuit connecting said stations, a vibrating element tuned to vibrate at a predetermined frequency corresponding to said fundamental frequency, a set of keys, means under the control of any one of said set of keys for amplifying a wave modulation of said fundamental frequency, and means individual to any key of said set for affecting a characteristic wave modulation for designating signal cycles.

17. In a system of telegraph signaling, a first

station, a second station, means common to said stations for supplying a current of fundamental wave frequency on a transmission circuit connecting said stations, apparatus at said stations including keyboard transmitting and rotary printing mechanisms having instrumentalities tuned to said fundamental frequency, means under the control of any one of the keys of said keyboard transmitting mechanism for modifying predetermined cycles of said current in accordance with elements of a character corresponding to the key operated, and means associated with said second station responsive to the modified cycles of said frequency current for initiating and controlling printing operations.

18. A method of signaling which includes the steps of transmitting a plurality of alternating current undulations of uniform amplitude constituting a signal, modifying the amplitude of certain ones of the undulations in accordance with fractional sign elements to be integrated during signal composition, and effecting printing operations under the control of said modified undulations for reproducing an integrated character by the initiation of a control magnet responsive to said modified undulations only.

19. In a signaling system, a transmitting station, transmitting apparatus at said station, a receiving station, means to transmit constant alternating current from said transmitting to said receiving stations, an element at said transmitting station responsive by oscillation to said alternating current frequency, a signal transmitting device at said transmitting station actuated by said element, and means for modifying an initial cycle of said alternating current and for coupling said oscillating element to the transmitting apparatus at said transmitting station.

LOUIS M. POTTS.
